W. M. GOODWIN

VALVE OPERATING MEANS FOR INTERNAL COMBUSTION ENGINES

FIG. 1. Filed March 5, 1919

FIG. 2.

INVENTOR,
W. M. Goodwin

BY Howard P. Denison
ATTORNEY.

UNITED STATES PATENT OFFICE.

WILLIAM M. GOODWIN, OF CENTRAL SQUARE, NEW YORK.

VALVE-OPERATING MEANS FOR INTERNAL-COMBUSTION ENGINES.

Application filed March 5, 1919. Serial No. 280,853.

To all whom it may concern:

Be it known that I, WILLIAM M. GOODWIN, a citizen of the United States of America, and resident of Central Square, in the county of Oswego, in the State of New York, have invented new and useful Improvements in Valve-Operating Means for Internal-Combustion Engines, of which the following, taken in connection with the accompanying drawings, is a full, clear, and exact description.

This invention relates to valve operating mechanism for internal combustion engines and refers more particularly to the means for transmitting motion from the cam shaft to the valves involving the use of a rocker contact between the cam and valve operating plunger somewhat similar to that set forth in my Patent #1,270,941, July 2nd, 1918, except as to certain details of construction and function hereinafter pointed out.

The main object is to provide the connection between each valve and its operating cam with means adjustable at will while the engine is in operation for varying the period of opening and closing of said valve.

Another object is to maintain noiseless contact between the various parts of the connection between the cam and valve. Other objects and uses relating to specific parts of the valve mechanism will be brought out in the following description.

In the drawings,—

Figure 1, is a vertical sectional view of a cam shaft and portion of the valve chamber showing a valve and means for transmitting motion from the cam to the valve together with the means for varying the period of opening and closing of the valve, the dotted lines indicating the limit of opening movement of the valve under normal or low speed conditions.

Figure 2, is a similar sectional view in which the means for varying the period of opening and closing of the valve is adjusted to a different position to cause the valve to open earlier and to close later than in the position shown in Figure 1, the dotted line

indicating the maximum opening of the valve as produced by said adjustment. 50

Figures 3 and 4 are detail section views taken respectively on lines 3—3 and 4—4 Figures 1 and 2.

Figure 5, is a detail sectional view taken on line 5—5, Figure 2.

The invention is adapted to be used in the operation of a valve —1— for controlling one of the ports as —2— of an internal combustion engine preferably of the four cycle type, and while it is shown as applied to side valves it is equally applicable to valves in the head.

As illustrated the valve is provided with a stem —3— movable in a vertical guide —4— and having its lower end provided with the usual collar —5— forming a seat for the lower end of a relatively stiff spring —6—, the upper end of which engages the under side of the adjacent portion of the engine frame —7— thereby placing the valve under spring tension to automatically close the same.

A cam shaft —8— may be supported in the usual manner upon the engine frame —7— and is provided with a cam —9— for opening the valve against the action of the spring —6— through the medium of suitable connections presently described.

A bushing —10— is tightly fitted within a suitable opening —11— in the frame —7— between the cam shaft —8— and lower end of the valve stem —3— for receiving and guiding a vertically movable plunger section —12— carrying at its lower end a rocker —13— for contact with the periphery 80 of the cam —9—.

This plunger section —12— is tubular and cylindrical and is held against rotary movement by a suitable key or pin —14— which is secured to the bushing —10— and projects into a vertically elongated slot —16— to permit said plunger section to reciprocate vertically without turning.

The lower end of the plunger section —12— is provided with a tubular head 90 —15— having spaced arms for receiving

trunnions —13'— on opposite ends of the rocker —13—, the head —15— being divided diametrically and transversely of the axis of the trunnions —13'— to permit the opposite halves to be readily fitted over and upon

5 said trunnions after which the head is tightly fitted within the lower end of the main body of its plunger section —12— to form substantially a unitary part thereof.

10 The lower face of the rock arm —13— which contacts with the periphery of the cam —9— is preferably concaved circumferentially of the cam and its central portion is substantially coincident with its axis of movement to avoid sliding contact with the periphery of the cam when moving about its axis thereby causing it to function more accurately in maintaining contact between the various parts of the connection 15 between the cam and valve as will be hereinafter more fully explained.

15 The axis of movement of the rocker and the vertical axis of the plunger are disposed in substantially the same vertical plane as that of the axis of the cam shaft —8— and 20 the valve stem —3— so that the transmission of motion from the cam to the valve may be as nearly as possible in a direct line.

25 A supplemental plunger —17— is reciprocally mounted within the plunger section —12— for vertical movement and has its lower end extending through the head —15— and provided with a cam face —18— for engagement with the upper convex face 30 of the rocker —13— at one side of the axis of the plunger section.

35 The lower end of the supplemental plunger —17— is preferably flattened to approximately the transverse width of the rocker —13— with which it is aligned and 40 its lower edge is inclined downwardly in a direction opposite to that of rotation of the cam —9— as indicated by arrow X Figures 1 and 2 so that the point of the cam will engage the upper face of the rocker at one 45 side of the vertical plane of its axis thereby causing the corresponding end of the rocker to be pressed into contact with the periphery of the revolving cam.

50 The upper end of the supplemental plunger —17— is socketed for receiving one end of a coil spring —19— having its opposite end seated in a similar but inverted socket in the lower end of a cam section —20— 55 which is secured by a pin —21— to and within the plunger section —12—.

60 The upper end of this cam section —20— is provided with opposed substantially semi-annular cams —22— both inclined in the same direction circumferentially to operate with similar substantially semi-annular cam members —23— on the lower end of a vertically movable head —24— which is also located within the upper end of a plunger section —12— and is secured

to the lower end of a vertically reciprocating valve operating rod —25—.

This rod —25— has its upper end threaded and provided with a screw cap —26— for direct contact with the lower end 70 of the valve stem —3— and is held in its adjusted position by a locknut —27—.

The upper end of the plunger section —12— is reduced and provided with a central lengthwise aperture —28— in which the 75 rod —25— is guided, the adjacent faces of the cam members —22— and —23— being held in contact by a coil spring —29— which is interposed between the head —24— and upper end of the plunger section —12—.

80 It is now clear that the cam —22— is movable vertically with the plunger section —12— but is held against turning movement by the pins —21— and —14— while the cam —23— is free to turn relatively to the cam —22— for the purpose of varying the time of opening and closing of the valve —1— relatively to certain positions of the valve operating cam —9—.

85 The means shown for turning the cam member —23— consist of a rotary head —30— journaled in the upper end of the bushing —10— around the adjacent end of the plunger section —12— and locked to the plunger rod —25— by means of a yoke 90 —31— having its central portion passed through an aperture in said rod and its opposite arms slidably engaged in apertures or sockets —32— in the head —30— so as to cause the rod with its cam member —23— 95 thereon to turn with said head.

100 Any suitable means may be provided for turning the head —30— and for this purpose it is provided with a laterally projecting arm —33— to which is connected an operating rod —34— by means of a swivel —35—.

105 The rod —34— may be connected in any well known manner to an operating handle or pedal within easy reaching distance of 110 the operator or driver.

115 In order that the adjacent ends of the plunger rod —25— and valve stem —3— may be held in contact at all times I have provided a light connecting rod —36— guided in an aperture —37— in the collar —5— at one side of the valve stem —3— and rod —25— and having its lower and upper ends provided with laterally projecting collars —38— and —39— slidably fitted 120 upon the rod —25— and valve stem —3— respectively, the lower collar —38— being engaged with the under side of the locknut —27— while the upper collar is engaged with the upper end of a relatively light 125 spring —40— having its lower end resting upon the collar —5— as shown more clearly in Figure —1—.

130 The springs —19—, —29— and —40— are all relatively light as compared with the

main spring —6— which is sufficiently stiff to excessively overcome the tension of all of the lighter springs and to assure the closing of the valve when the lower points of the 5 main cam —9— are registered with the rocker —13—.

The head —20— is held against upward displacement by means of a shoulder —41— movably secured to the upper end of the 10 bushing —10— so as to slightly over-hang one side of the head —30— as shown in Figures 1, 2 and 4.

It will now be seen that a rigid connection is established between the axis of the rocker 15 —13— and lower end of the valve stem —3— through the medium of the plunger section —12—, pin —21—, cam members —22— and —23— and rod —25— and that the rocker —13— is yieldingly held in contact 20 with the periphery of the main cam —9— by means of the spring —19— which also cooperates with the spring —29— to maintain yielding contact between the cam members —22— and —23— and also by the 25 spring —40— to maintain yielding contact between the rod —25— and valve stem —3— thereby preventing lost motion between those parts and obviating the hammering noise due to such lost motion.

30 It is obvious that the downward movement of the plunger section —12— carrying the rocker —13— is limited by the closing of the valve —1— under the tension of the main spring —6— and that when the main cam —9— and cam members —22— and —23— are in the positions shown in Figure 1 the axis or longitudinal center of the lower bearing face of the rocker —13— will be some distance above the low side of the 35 main cam —9— at which time the point of the cam —18— under the tension of the spring —19— will tilt the rocker —13— at an angle to the axis of the plunger section —12— to cause the rocker to engage the periphery of the main cam —9— some distance to one side of its axis so that the point of contact between the rocker and cams —9— and —18— will be at the side of the axis of the rocker opposite the direction of rotation 40 of the main cam —9— to prevent lost motion and resultant noise as the main cam —9— is rotated.

45 This appreciable space between the low point of the main cam —9— and central bearing point or axis of the rocker —13— permits a corresponding lowering of the plunger section —12— and rocker —13— carried thereby against the action of the spring —19— for the purpose of varying 50 the time of opening and closing of the valve —1— and incidentally increasing the vertical movement of said valve as indicated by dotted lines in Figure 2. This downward movement of the plunger section —12— and rocker —13— is effected by turning the cam

member —23— from the position shown in Figure 1, to or toward the position shown in Figure 2.

For example, assuming that the valve 55 —1— is closed, then turning the cam section —23— from the position shown in Figure 1, will force the plunger section —12— downwardly against the action of the springs —19— and —29— which may be continued until the central bearing point or 60 axis of the rocker is in contact with the low point of the main cam —9— thereby establishing a rigid connection between the main cam —9— and valve stem —3— for lifting the valve from its seat as the main cam is rotated.

65 If the parts of the valve operating mechanism are in the position shown in Figure 2 and the main cam —9— is rotated in the direction indicated by arrow X, the inclined 70 side of the main cam approaching the axis of the rocker will gradually ride against the nearest end of the rocker engaged by the point of the cam —18— while the opposite end of the rocker will be engaged with the 75 periphery of the cam at the opposite side of the axis, thus causing the main cam to exert an upward lift upon the valve operating mechanism earlier in the rotation of the high 80 point of the cam and will also open the valve 85 to a greater extent than when the cam members —22— and —23— are in their normal 90 positions, the object of which is to increase the period of intake and exhaust of the gases as the speed of the engine increases and 95 thereby to maintain a proportionately increased power under high speed and a reduced fuel consumption under low speed.

100 What I claim is:

1. In combination with a cam shaft and 105 spring closed valve of an internal combustion engine, means actuated by the cam on said shaft for opening the valve against the action of its closing spring including a plunger, and a rocker spring-pressed against 110 the cam and having a cam-engaging face passing through its axis of movement.

2. In combination with a cam shaft and 115 a spring closed valve of an internal combustion engine, means actuated by the cam on said shaft for opening the valve against the action of its closing spring including a plunger and a rocker having a concave bearing face passing through its axis, said rocker 120 being spring pressed into engagement with the cam.

3. In combination with a cam shaft and a self closing valve of an internal combustion engine, a plunger, a rocking member pivoted to the plunger and provided with a contact 125 face engaging the cam, said contact face passing through the axis of movement of said rocking member, and means for transmitting motion from the plunger to the valve.

4. Valve operating means for internal combustion engines comprising in combination with a cam shaft, a spring-seat on the valve stem, a relatively stiff coil spring encircling the valve stem and bearing against said seat to close the valve, a tappet engaged with the valve stem to open the valve against the action of the spring, means actuated by the cam shaft for operating the tappet, a 10 relatively light coil spring encircling the valve stem within the first named spring,

and a connecting member between the tappet and said relatively light spring for holding the tappet in contact with the valve stem.

In witness whereof I have hereunto set ¹⁵ my hand this 25th day of February, 1919.

WILLIAM M. GOODWIN.
